UNITED STATES PATENT OFFICE

CHARLES HLAVATY, OF NEW YORK, N. Y.

ROTARY RADIATOR

Application filed August 1, 1928. Serial No. 296,805.

My invention relates to radiators of a general type suitable for cooling heated mechanism by means of a forced circulation of air.

While my invention admits of general use, it is of special service in connection with radiators employed for cooling internal combustion engines, for instance, as connected with the water jackets of engines used upon automobiles.

More particularly stated, I give my radiator the form of a rotary fan, so constructed and arranged that hot water, steam or the like is caused to circulate within the blades of the fan while the latter are rotating, the radiator while in action being continuously cooled by its contact with air which it causes to circulate.

My invention further comprehends using my rotary radiator as a fan, for the purpose of continuously impelling free air against and around an internal combustion engine or the like, so as to cool it by acting upon it as a fan, independently of any cooling action as a radiator.

In addition, my invention comprehends various improvements in radiators and parts immediately associated therewith, for the purpose of increasing their efficiency.

Reference is made to the drawings forming a part of this specification, and in which like reference characters indicate like parts throughout all of the figures.

Figure 1 is a fragmentary side elevation of my improved radiator and certain parts used therewith, as adapted for use in connection with the internal combustion engine of an automobile.

Figure 2 is a fragmentary end elevation of the mechanism shown in Figure 1.

Figure 3 is a substantially central vertical section through the mechanism shown in Figure 1.

Figure 4 is a side elevation of the mechanism appearing in Figure 1, as mounted for use upon the internal combustion engine of an automobile.

Figure 5 is a cross section through one of the radiator sections having the form of fan blades.

Referring to Figure 4 the crank case ap-

pears at 6, the shaft housing at 7, a water jacket at 8 and a countershaft at 9.

Mounted upon the counter-shaft 9 and revoluble therewith is a pulley 10, and engaging this pulley and driven thereby is a belt 11.

The belt 11 also engages a pulley 12, shown more particularly in Figure 3.

The pulley 12 is carried by and practically forms a part of a revoluble sleeve 13, this sleeve having a portion 14, the internal diameter of which is relatively large, as indicated in Figure 3.

Extending concentrically through the sleeve 13 is a neck 15, having the general form of a cylinder, and carried by a gear case 16.

The gear case 16 has substantially the form of a mutilated sphere, and is provided with an upwardly extending cylindrical portion 17.

Fitted into the cylindrical portion 17 is a pipe 18, which leads to and is connected with the upper portion of the water jacket 18 as shown more particularly in Figure 4.

A packing 19 having an annular form as indicated in Figure 3, encircles the neck 15 and fits into the sleeve 13. This packing is engaged by a gland 20 of annular form, which encircles the neck 15 and is located within the portion 14 of the sleeve 13.

Also located within the portion 14 is a ball bearing, consisting of annular members 21 and 22 separated by balls 23. The annular member 21 engages the gland 20 and holds it against the packing 19.

An adjusting ring 24 is carried by the portion 14, into which it is screwed, so as to bring it into engagement with the annular member 21 of the ball bearing.

By turning the adjusting ring 24 and thus moving it slightly to the right or left according to Figure 3, the pressure of the gland 20 against the packing 19 may be adjusted as required.

The sleeve 13 is provided with a hub flange 25, integral with it, as indicated in Figure 3.

Engaging the hub flange 25 are hollow blades 26, in this instance five in number, as may be understood more particularly from Figure 2.

Each blade 26 is provided externally with ribs 27, made of metal and having such form as to facilitate the radiation of heat from the blade.

5 Mating the hub flange 25 is another hub flange 28. Each blade 26 engages both of the hub flanges 25 and 28, and is fixed in position relatively thereto by means of bolts 29.

10 A tubular shaft 30 extends from the hub flange 28 through the sleeve 15, and is concentric to the latter, as indicated in Figure 3. The tubular shaft 30 is adapted to turn, as hereinafter more fully described, the sleeve 15 being stationary.

15 Each hollow blade 26 is provided with a partition 31, of the form shown more particularly in Figures 3 and 5. This partition extends from the tubular shaft 30 radially outward, nearly but not quite to the outer end of the blade, as may be understood from Figure 3.

20 By this arrangement there is formed on one side of the partition 31 a channel 32, and on the opposite side of this partition, another channel 33, these two channels being connected with each other and rendered practically continuous by a passage 34, as indicated more particularly in Figure 3.

25 The tubular shaft 30, near its outer or free end, is provided with a number of ports 35, one for each blade 26, these ports being so arranged as to maintain communication between the passages 33 of the blades and the passage through the tubular shaft 30, this last mentioned passage being shown at 36.

30 The tubular shaft 30 is so spaced from the neck 15 as to form between these parts an annular passage 37, shown more particularly in Figure 3.

35 The hub flange 28 carries a closure plug 38, fitted into position by aid of a gasket 39. By removing the closure plug 38, access may be had to the passage 36 and ports 35.

40 The nipple 17 is provided with a passage 40, shown more particularly in Figure 3, and by means of this passage communication is maintained between the pipe 18 and the annular passage 37.

45 Detachably mounted upon the tubular shaft 30 and normally revoluble therewith is a bevel gear 41, having a general annular form as indicated in Figure 3. This bevel gear engages a stationary shoulder 42 with which the gear case is provided, the shoulder 50 serving as a bearing for the bevel gear.

55 Located within the gear case 16 and meshing with the bevel gear 41, is another bevel gear 43, mounted upon a revoluble shaft 44, this shaft being journaled within the gear case.

60 Mounted upon the lower end of the gear case is a small pump 45 of the centrifugal type. This pump is connected with and driven by revoluble shaft 44. A pipe 46 extends from the pump 45 to the bottom of the

water jacket 8. The pump while in action forces water continuously into the water jacket. A small closure cap 47 protects the upper end of the shaft 44 from the entrance of dust and dirt. A larger closure cap 48 normally closes the gear case 16. By removing the closure cap 48, the operator may have access to the interior of the gear case.

65 The course of the hot water to be cooled by my invention may be traced as follows: The water being forced by the pump 45 through the pipe 46 enters the bottom of the water jacket 8, which is normally full of water. From the top of the water jacket the water passes through the pipe 18 and nipple 17, following the passage 40, shown more particularly in Figure 3, into the annular passage 37; then passing to the left according to Figure 3, the water passes radially outward following the passages 32 out to the passages 34 and thence radially inward, through passages 33 and ports 35. Thence the water follows the passage 36 into the gear case 16, and from here it passes downwardly into the pump 45.

70 Thus there is a circulation of the water continuously so long as the pump 45 is in operation. It will be noted that the water divides and passes through the several blades 26, and that in passing through each blade it goes radially outward to the end of the blade, and thence returns radially inward.

75 The radiator as a whole, comprising as it does a number of sections each having the proximate form of a fan blade, has the form of a rotary fan, which turns upon the neck 15. Because the tubular shaft 30, which turns with the fan, extends entirely through the neck 15 and through the bearing 42 against which the bevel gear 41 presses constantly while rotating, the radiator cannot be displaced to the left, according to Figure 3. By this arrangement the sleeve 13 with all of its contents may rotate freely upon the neck 15, and the packing 19 as well as the ball bearing can be adjusted with great exactness and without regard for any stationary part. In other words, the sleeve 13 and parts carried by it, are as far as possible self-contained and adjustable independently of other parts, their functions being thus greatly simplified.

80 A post 49, connected with the gear case 16, serves as a mounting for this gear case and parts carried thereby.

85 The radiator is driven by the belt 11, acting upon the pulley 12, the belt 11 being driven by the pulley 10 which is turned by the counter-shaft 9.

90 As shown in Figure 4, the radiator is so located relatively to the water jacket and other parts having normally high temperatures that, serving as a fan, it drives continuously a current of relatively cool air against and around these heated parts, so as to cool them.

It will be understood, that my radiator has two distinct functions, each general in its character. First, it acts like any other radiator used to cool water which has been heated, except that the radiator turns through the air instead of the radiator being stationary and the air being circulated through and around it. Second, it serves as a fan for supplying relatively cool air to the water jacket and causing this air, by its contact with the water jacket, to further remove heat therefrom, after the manner of an ordinary rotary fan used for such purpose.

A grating 50 may, if desired, be so positioned as to protect the fan from injury, and to protect persons from injury by the rotation of the blades, this feature being old and well known.

I do not limit myself to the use of my invention upon automobiles nor upon internal combustion engines, nor to any particular form of my device, except as limited by my claim, the scope of which is commensurate with my invention.

Having thus described my invention, what I claim as new and desire to secure by Letters Patent is as follows:

1. The combination of a journal neck of substantially cylindrical form, means for supporting said journal neck in a stationary position, a tubular shaft extending through said journal neck and revolute relatively thereto, a radiator connected with said tubular shaft and therewith revolute relatively to said journal neck, a revolute sleeve connected with said radiator, means for actuating said revolute sleeve and thereby turning said radiator and said tubular shaft, a stuffing box carried by said sleeve and engaging said journal neck, said stuffing box including a gland movable relatively to said sleeve for the purpose of adjusting said stuffing box relatively to said journal neck, a ball bearing provided with an inner member of annular form fixed upon said journal neck and an outer member of annular form fitting loosely into said revolute sleeve and engaging said gland, and means for adjusting said outer member of annular form relatively to said sleeve, and thereby adjusting said gland.

2. The combination of a journal neck of substantially cylindrical form, means for supporting said journal neck in a stationary position, a tubular shaft extending through said journal neck and revolute relatively thereto, a radiator connected with said tubular shaft and therewith revolute relatively to said journal neck, a revolute sleeve connected with said radiator, means for actuating said revolute sleeve and thereby turning said radiator and said tubular shaft, a stuffing box carried by said sleeve and engaging said journal neck, said stuffing box including a gland movable relatively to said sleeve for the purpose of adjusting said stuf-

fing box relatively to said journal neck, and means for adjusting said outer member of annular form relatively to said sleeve, and thereby adjusting said gland.

3. The combination of a journal neck of substantially cylindrical form, means for supporting said journal neck in a stationary position, a tubular shaft extending through said journal neck and revolute relatively thereto, a radiator connected with said tubular shaft and therewith revolute relatively to said journal neck, a revolute sleeve connected with said radiator and mounted upon said journal neck, means for actuating said revolute sleeve and thereby turning said radiator and said tubular shaft, a globe casing connected with said journal neck, gearing mounted within said globe casing and connected with said revolute shaft, and a pump mounted upon said globe casing and communicating with said radiator through the medium of said revolute shaft for the purpose of forcing through said radiator a liquid to be cooled.

Signed at New York city, in the county of New York and State of New York, this twenty-second day of July, 1927.

CHARLES HLAVATY.
